[57] CLAIM

The ornamental design for a razor handle, as shown and described.

DESCRIPTION

FIG. 1 is a top plan view of the razor handle;
FIG. 2 is a side view of the razor handle, with the opposing side view being a mirror image of FIG. 2;
FIG. 3 is bottom view of the razor handle;
FIG. 4 is a cross-sectional view of the razor handle taken along line 4—4 of FIG. 2;
FIG. 5 is a cross-sectional view of the razor handle taken along line 5—5 of FIG. 2; and,
FIG. 6 is a cross-sectional view of the razor handle taken along line 6—6 of FIG. 2.
The undisclosed surfaces of the structures at the front of the razor follow the contours of the surfaces shown.
